UNITED STATES PATENT OFFICE.

EDWARD MELTZER, OF NEW YORK, N. Y., ASSIGNOR TO HYDROCARBON BURNER & MANUFACTURING COMPANY, OF HOBOKEN, NEW JERSEY, A CORPORATION OF NEW JERSEY.

HYDROCARBON VAPORIZER AND BURNER.

1,113,231.

Specification of Letters Patent.

Patented Oct. 13, 1914.

Application filed March 5, 1910. Serial No. 547,402.

To all whom it may concern:

Be it known that I, EDWARD MELTZER, a citizen of the United States, residing in the city of New York, borough of Manhattan, 5 county and State of New York, have invented a certain new and useful Hydrocarbon Vaporizer and Burner, of which the following is a specification.

This invention is a hydrocarbon vaporizer 10 and burner, and embodies an improvement, in a certain particular, upon the apparatus disclosed in a prior application filed by me on Nov. 19, 1908, Serial No. 463,814.

In the apparatus described in the afore- 15 said application, a gaseous fluid, under pressure, preferably steam, is permitted to enter a series of nozzles, and the suction produced thereby operates to draw in and commingle with said steam, petroleum and air, thereby 20 producing a suitable gaseous combustible mixture. In said apparatus, however, the steam is superheated but no means is provided for preheating the oil.

The object of the present invention is to 25 increase the efficiency of the apparatus forming the subject matter of said prior application, and with this object in view, embodies means for preheating the petroleum or other combustible, prior to mixing it with 30 the steam or air.

In the preferred embodiment of the invention, the oil is heated by causing it to circulate in a pipe, coil or other container, while said container is exposed to the heating action 35 of the superheated steam employed in the apparatus.

In the accompanying drawings I have 40 illustrated one practical embodiment of the invention, but the construction shown there- in is to be understood as illustrative, only, and not as defining the limits of the invention.

Figure 1 is a plan view of a vaporizing burner embodying this invention. Fig. 2 is 45 an enlarged vertical sectional elevation on line 2—2 of Figs. 1 and 3. Fig. 3 is a vertical sectional elevation on line 3—3 of Fig. 2. Fig. 4 is a plan view of a portion of the burner.

The burner, or more properly a combined 50 vaporizer and burner, consists of a cylinder, A, provided at one end with a frusto conical head, a'; and a vaporizing plate, B. Said head has a series of apertures or openings, 55 a', for the ingress of air into cylinder or

chamber, A, and, also, other larger apertures, e, which are adapted to be partly or wholly closed by suitable shutters, C, thereby providing for regulating the volume of air supplied to the apparatus.

D designates a casting which is supported 60 on a shelf, d', suspended from the cylinder, A, said casting being provided with an interior chamber, e, termed a steam chamber, preferably annular in shape, and connected with such chamber is means for supplying it with steam.

As shown, a steam pipe, E, is attached to casting, D, whereby steam under pressure is introduced in said chamber, e. The steam 70 pipe, E, is preferably extended forwardly of the burner and within the path of the products of combustion, whereby the steam becomes superheated prior to its introduction into chamber, e.

Casting, D, is provided with a front plate, e', and a rear plate, e'', said front and rear plates forming, respectively, the front and rear walls of chamber, e. Plate, e', is preferably made integral with casting, D, but 80 plate, e'', is removable to permit of the introduction of an oil coil, J, within the steam chamber, e. The front plate or head, e', is provided with a series of openings, f, corresponding in number and position to openings, b, of vaporizing plate, B, and in these openings, f, are screwed jet nozzles, F. Said nozzles are tapered and extend forwardly from plate or head, e', into the openings, b, said nozzles being of less diameter than the openings, b, whereby free spaces are provided between the walk of openings b, and the outer surfaces of nozzles, F.

The burner is provided with means for removing any sediment which may lodge or accumulate in openings, b, of the vaporizing plate, B, or in the passages of nozzles, F, whereby the steam passage or passages may be kept in an unobstructed condition, and thus permit the steam and combustible vapor to pass freely therethrough. As shown, the sediment removing means consists of stems or spindles, G, extending through stuffing boxes, g, and by reciprocating said spindles when required, it will be obvious 100 that openings, b and f, may be kept clear.

The salient feature of the present invention consists in preheating the oil, preferably in the steam chamber, e, and, with this object in view, an oil pipe, J, having an 110

- inlet pipe, *j*, is coiled within said chamber so that oil passing through said coil becomes pre-heated by the steam contacting with the exterior of said coil. As shown more clearly 5 in Fig. 3, casting, *D*, is provided with a hub or sleeve, *i*, and into this sleeve is fitted and second a short tube, *I*, which may be termed an oil vaporizing chamber the inner end of which is positioned opposite to a depression, *b'*, in the vaporizing plate, *B*. The outer end of tube, *I*, is closed by head, *i'*, and to this head is attached one end, *j'*, of the oil pipe, *J*, whereby the preheated oil is supplied to tube, *I*, and the chamber of 15 said tube *I* constitutes a vaporizing chamber for the reason that the preheated oil is converted into vapor within the chamber of said tube *I*. The oil is fed to the pipe, *J*, preferably by means of the suction produced by the steam passing through openings, *f* and *b*. Oil pipe, *j*, is provided near its inlet to the burner with a valve, *j²*, whereby the amount of oil supplied to the burner may be controlled or regulated.
- 20 25 K designates a pipe attached to casting, *D*, and communicating with chamber, *e*, so as to carry off any water of condensation which may accumulate in chamber, *e*, said pipe being provided with a stop cock, *k*.
- 30 35 The operation of the apparatus will be apparent from the foregoing description, but it may be described as follows:—Steam from any suitable source is supplied to pipe, *E*, is superheated therein, and conveyed thereby to chamber, *e*, whereas the oil, pre-heated in pipe, *J*, is fed thereby into tube, *I*, and projected in the form of a spray or jet against the depression, *b*, in vaporizing plate, *B*. The steam issues from nozzles, *F*, in the form of jets which are projected through openings, *b*, into the mixing chamber of cylinder, *A*, and these steam jets draw or entrain the vaporized fuel into said mixing chamber. Simultaneously with these 40 45 operations, air is drawn or exhausted into the chamber of cylinder, *A*, and the steam, fuel and air are thus thoroughly commingled in said chamber and ignited therein. The combustion thus set up heats vaporizing
- plate, *B*, sufficiently to vaporize, in whole 50 or in part, the oil thrown against it, which vapor is then entrained by the jets from nozzles, *F*, and passes through openings, *b*, into the chamber of cylinder, *A*, which latter may be properly termed a mixing chamber. 55
- Having thus fully described the invention, what I claim as new, and desire to secure by Letters Patent is:
1. In a hydrocarbon vaporizer and burner, the combination of an oil vaporizing 60 chamber, a heating chamber externally of said vaporizing chamber, means for introducing a heating agent to said heating chamber, a coiled oil pipe within said heating chamber, an oil vaporizing plate provided with openings, and passages leading from the vaporizing chamber and heating chamber to the said openings in the vaporizing plate.
2. In a hydrocarbon vaporizer and burner, 70 the combination of an oil vaporizing chamber, a heating chamber externally of said vaporizing chamber, means for introducing a heating agent to said heating chamber, a coiled oil pipe within said heating chamber, 75 an oil vaporizing plate provided with openings, passages leading from the vaporizing chamber and heating chamber to the said openings in the vaporizing plate, and a mixing chamber forwardly of the vaporizing plate into which the openings in the vaporizing plate lead.
3. In a hydrocarbon vaporizer and burner, the combination of an oil vaporizing chamber, a heating chamber externally of said 80 vaporizing chamber, means for introducing a heating agent to said heating chamber, a coiled oil pipe within said heating chamber, said heating chamber being provided with a detachable plate for introducing the coiled 85 oil pipe therein.

In testimony whereof I have signed my name to this specification in the presence of two subscribing witnesses.

EDWARD MELTZER.
